UNITED STATES PATENT OFFICE.

FRANCISCUS L. VAN WEELEN, OF ROTTERDAM, NETHERLANDS, ASSIGNOR TO U. S. SLICING MACHINE COMPANY, OF LA PORTE, INDIANA, A CORPORATION OF INDIANA.

FEED MECHANISM FOR SLICING MACHINES.

Application filed October 8, 1927, Serial No. 224,828, and in Germany December 23, 1926.

This invention relates to mechanism for producing a step by step movement of the work support for feeding the material toward the slicing machine knife and has for 5 its object the provision of a feeding mechanism having, in addition to the usual adjustment for thin and medium slices, a coarser adjustment than has heretofore been possible for thicker slices. Other objects 10 and advantages will appear from the following description.

The invention is exemplified in the combination and arrangement of parts shown in the accompanying drawing, and described 15 in the following specification, and it is more particularly pointed out in the appended claims.

In the drawing:—

Fig. 1 is an elevation of a slicing machine 20 having one embodiment of the present invention applied thereto;

Fig. 2 is an elevation of the feed mechanism on a larger scale than that shown in Fig. 1;

Fig. 3 is a somewhat diagrammatic approximately horizontal section view of the feed mechanism.

In the drawing, the numeral 10 designates the base of a slicing machine having a rotary 30 circular slicing knife 11 and a feed table 12. The feed table 12 is reciprocated in the usual way by a crank 13 and connecting rod 14 operated by a hand wheel 15. A feed screw 16 is journaled in a bearing 17 on the table 12 and is provided with a projecting spindle 18 having an arm 19 pivoted thereon. The arm 19 is held against a stop pin 20 by a spring 21 and is arranged to engage an adjustable fixed stop 22 by means of which the 35 arm 19 is swung downwardly and rearwardly against the tension of the spring 21 when the table 12 moves to its forward position. A gear segment 23 is formed integral with the arm 19 and meshes with a pinion 24 carried by a stud shaft 25 journaled in a link 26 pivotally mounted on the spindle 18. The 45 opposite end of the stud shaft 25 from the pinion 24 carries a gear 27 which meshes with a pinion 28 journaled on the spindle 18.

An arm 29 is formed integral with the pinion 28 and carries a pawl 30 pivotally mounted at 31 thereon. The pawl 30 engages a ratchet wheel 32 fixed to the spindle 18. The 50 link 26 has an angular projection 33 which carries a spring-held pin 34 arranged to engage an opening 35 in the arm 19, thus locking the link 26 to the arm 19. When the parts are thus engaged, it will be apparent that the cam arm 19 and the pawl arm 29 will be rigidly held together and will rotate 60 in unison upon the spindle 18. This is the arrangement employed for the usual thin slices of meat. Each time the table is moved forward, the cam arm 19 will strike the stop 22 and the pawl 30 will rotate the spindle 18 and feed screw 16 a small amount to feed the meat support on the table 12 toward the slicing knife in the well-known manner. The amount of rotation of the feed screw 65 may be varied by adjusting the stop 22 in its support.

When it is desired to cut thick slices, the pin 34 will be withdrawn from the opening 35 and inserted in an opening 36 in the stop pin 20. This will hold the link 26 in fixed 75 position so that when the cam arm 19 is oscillated upon its spindle 18, the pinion 24 will be rotated by the gear segment 23 causing the gear 27 to drive the pinion 28 which carries the pawl arm 29. It will be seen from Fig. 3 that the gear ratio is such that the 80 rotation is increased by the interposed gears 24 and 27 so that a much greater movement will be imparted to the pawl arm 29 and consequently to the feed screw 16 than would be 85 the case if the arms 19 and 29 were moved in unison. In this way, a much coarser adjustment is provided for cutting thick slices.

It is apparent that the coarser slices may be varied in thickness by adjusting the stop 90 22 in the same way that the thickness of the finer slices is adjusted.

I claim:—

1. In a slicing machine having a rotary slicing knife and a reciprocating work support, a feed screw, means for imparting step by step movement to said feed screw, and a motion increasing device arranged to be interposed between said last-named means and feed screw, and means for rendering 95 said motion increasing device inoperative.

2. In a slicing machine, a feed screw, a reciprocating member for imparting movement to said feed screw, adjustable means for operating said reciprocating member to 100 impart various movements to said recipro-

- cating member, and means for changing the amount of movement imparted to said feed screw for a given movement of said reciprocating member.
3. In a slicing machine, a feed screw, pawl and ratchet mechanism for operating said feed screw, an arm for operating said pawl and ratchet mechanism, an adjustable stop for operating said arm, and adjustable speed changing mechanism interposed between said arm and pawl and ratchet mechanism.
4. In a slicing machine, a feed screw, means for operating said feed screw to control the thickness of slices produced by said slicing machine, said operating means being adjustable to produce different thicknesses of slices, and an adjustable connection between said operating means and feed screw for imparting different amounts of movement to said feed screw for a given movement of said operating means.
5. In a slicing machine, a feed screw, ratchet mechanism for operating said feed screw, an arm for operating said ratchet mechanism, means for imparting various movements to said arm, and means for changing the amount of movement imparted to said ratchet mechanism for a given movement of said arm.
6. In a slicing machine, a feed screw, ratchet mechanism for operating said feed screw, an arm for operating said ratchet mechanism, motion increasing gearing interposed between said arm and ratchet mechanism, and means for rendering said gearing inoperative.
7. In a slicing machine, a feed screw, ratchet mechanism for operating said feed screw, an arm for operating said ratchet mechanism, gearing interposed between said arm and ratchet mechanism for increasing the movement between said arm and ratchet mechanism, and means for locking said arm and gearing together to prevent increase of motion by said gearing.
8. In a slicing machine, a feed screw, ratchet mechanism for operating said feed screw, an arm for operating said ratchet mechanism, gearing interposed between said arm and ratchet mechanism, a movable member for supporting said gearing, and means for locking said movable member in fixed position to produce increased motion of said ratchet mechanism by said arm.
9. In a slicing machine, a feed screw, 55 ratchet mechanism for operating said feed screw, an arm journaled on said feed screw, an adjustable stop for operating said arm, gearing interposed between said arm and ratchet mechanism, a movable member for supporting said gearing, and locking means arranged to hold said member either in fixed position or in fixed relation to said arm to cause said arm to impart different amounts of movement to said feed screw for 60 a given movement of said arm.
10. In a slicing machine, a feed screw, mechanism for imparting step by step rotation to said screw, a movable arm for actuating said mechanism, a member for moving 70 said arm to actuate said mechanism, said arm and member being relatively adjustable to vary the amount of rotary movement imparted to said screw by said arm and mechanism, and means co-operating with said arm 75 and mechanism inoperative in one position to affect the rotary movement imparted to said screw by said arm and mechanism but operative in another position to change the magnitude of rotary movement imparted to 80 said screw by said arm and mechanism from that imparted thereto by said arm and mechanism in any position of adjustment between said arm and member.
11. In a slicing machine, having a reciprocating carriage and a feed screw, a pawl and ratchet for imparting step by step rotation to said screw, an adjustable abutment 85 stationary with respect to said carriage, an arm on said carriage movable by said abutment, a second movable arm on said carriage, co-operating gearing between said second arm and ratchet rotatable by gearing between said first and second arms, 90 means for detachably connecting said second arm to said first arm to move in unison with said pawl and first arm, and means for holding said second arm stationary with respect to said first arm to actuate said pawl by rotation of said gearing.
- 100 In testimony whereof I have signed my name to this specification on this 24th day of September, A. D. 1927.
- FRANCISCUS L. VAN WEELEN.
